J. M. LAWLOR

OPTICIAN'S TOOL

Filed May 20, 1921

UNITED STATES PATENT OFFICE.

JAMES M. LAWLOR, OF TOPEKA, KANSAS, ASSIGNOR OF ONE-HALF TO T. H. CUTSINGER,
OF TOPEKA, KANSAS.

OPTICIAN'S TOOL.

Application filed May 20, 1921. Serial No. 471,138.

To all whom it may concern:

Be it known that I, JAMES M. LAWLOR, a citizen of the United States, residing at Topeka, in the county of Shawnee and State of Kansas, have invented certain new and useful Improvements in Opticians' Tools; and I do declare the following to be a full, clear, and exact description of the invention, such as will enable others skilled in the art 10 to which it appertains to make and use the same, reference being had to the accompanying drawings, and to the figures of reference marked thereon, which form a part of this specification.

15 This invention relates to opticians' tools and particularly to a tool adapted to be used as a pincers or clamp for assembling eye-glass mountings, for effecting adjustments and for use in connection with the general 20 organization of such mountings, the invention being particularly applicable for remounting and replacing lens frames.

One of the purposes of my invention is to provide a tool which is capable of effectively 25 crimping or pincing the rim clamps at the ends of the bridge piece to the lens frames in such a manner that a tight union will be provided between the clamped lens frames and between the lens frames and the lenses 30 without liability of crushing the edges of the lenses.

It is also the purpose of my invention to provide an improved tool which is adapted 35 to be utilized as a hand clamp for efficiently holding the mounting so that the bridge may be bent to provide the proper adjustment to conform to the shape of the nose of the person wearing the glasses, the device being also capable of holding the mounting in 40 clamped position for effecting the requisite adjustments and assembly of the nose clamp, finger pieces, etc.

There is means provided for holding the lens frame in proper position with respect 45 to the rim clamps preparatory to effecting the crimping or pincing operation.

Means is also provided for expanding the rim clamps and for efficiently holding the eye-glass mountings so that they can be 50 worked upon.

Among the manifold advantages of my invention is the provision of means whereby the jaws of the tool will be normally closed so as to hold the work without requiring 55 pressure on the handles, the handles being

pressed to release the work. The jaws clamp the frame and the clamps for the frame. These jaws, in their operative position, are at right angles to the plane of the frame so that pressure across the plane of the frame will be exerted in opposite directions and in such a manner that the requisite amount of pressure can be had to cause the clamps to grip over the celluloid frame. The 60 clamping jaws are adapted to engage the clamps without the necessity of removing the nose clamps or guards, the springs or the screws from the nose pieces, an advantage 65 over known types of opticians' tools.

Another advantage is that the clamps can 70 be tightened on the frame without removing the lenses and when it is necessary to repair the lens mountings, the celluloid frames can be burnt out of the clamps and the clamps expanded to receive the rims of 75 the frames, which may be held in place until they are secured by pressure from the tool to cause the clamps on the nose pieces to properly engage them.

The particularly novel features of my invention will be apparent by reference to the accompanying drawings, in which

Fig. 1 is a perspective view of a tool constructed in accordance with my invention.

Fig. 2 is a similar view of the side opposite to Fig. 1.

Fig. 3 is a sectional view on the line 3—3 of Fig. 2.

Fig. 4 is a perspective view of the upper portion of the tool, showing it in operative 90 position.

Fig. 5 is a cross sectional view through the tool, showing the lens frame positioning member.

Fig. 6 is an enlarged elevational view 95 showing the expanding jaws in functional position, and

Fig. 7 is a perspective view of the upper portion of a modified form of tool.

1 designates a rigid jaw at the end of a 100 handle or grip 2 rigid therewith. The jaw 1 consists of a straight bar against which one edge of a complementary or movable jaw bar 3 bears, the movable jaw having sliding contact therewith through the me- 105 dium of a handle or grip 4, which is pivot- ed thereto at 5 and which has a laterally pro- jecting arm 6 pivoted to the rigid jaw 1 at 7. The movable jaw has a lateral extension or beak 8, which has parallel movement with 110

respect to the co-operating face 9 at the upper end of the bar or jaw 1 and it is normally held in gripping position by a tension spring 10, one end of which is fastened 5 to the movable jaw at 11 and the other end to the rigid jaw at 12 (see Fig. 1). Therefore, the two jaws will be held in co-operative position and the gripping face of one jaw will always be parallel with the gripping face of the other jaw to exert a uniform pressure on the rim clamps or lens frames or both when the device is functioning.

The jaw bars 1 and 3 are held in intimate 15 contact by a loop or strap 13, which is rigid with the rigid jaw and embraces part of the movable jaw, as clearly seen in Figs. 1 and 2.

The jaws can be spread apart by spreading the handles 2 and 4 and since the spring 20 10 tends to close the jaws, it will be apparent that in order to grip the material, the handles 2 and 4 must be moved apart and as soon as pressure is released, the spring will bring the jaws back to clamping position.

25 The right angular portion 8 of the jaw bar 3 is provided with a groove 14 in line with a groove 15 in the rigid jaw 1. This is for the purpose of permitting the finger piece 16 to lie in the groove 14 and the nose clamp 30 stem 17 for the nose clamp 18 to lie in the groove 15, the nose clamp 18 being receivable in the transverse groove 19 in the jaw 1 and the aligning recess 20 in the jaw stem or bar 3. The grooves allow the jaws to 35 readily clamp the clamps 21 on the ends of the bridge 22 and cause the clamps to bind upon the grooved frames 23 to secure the lenses in place.

The jaws 1 and 3 are provided with 40 grooves 24 and 25 to provide for the transverse curvature of the frames, and the jaws lengthwise are preferably formed on arcs shorter than the arcs from which the curved portions of the clamps 21 are formed so that 45 the edges of the clamps will be tightly bound upon the frames 23.

It is to be understood, of course, that the mounting may be inverted with respect to the position shown in Fig. 4 if desired, but 50 ordinarily, the clamps 21 will be pinched upon the frames to the position shown although I do not wish to be limited to this particular position of the tool in making the adjustments.

55 The handle 2 is provided with a shoulder 26, against which the lower edge 27 of the handle 4 may rest so that the clamping movement of the jaw portions 8 and 9 will be limited to prevent the jaws coming too 60 tightly together so as to crush the clamps 21. In other words, the meeting faces of the jaws may come together sufficiently to crimp the clamps 21 but not sufficient to crush them.

65 The jaw bars 1 and 3 are provided with

expander elements which consist of two normally open, groove-engaging beaks or blades 28 and 29 projecting from the front edge of the rigid jaw bar 1. The blade or beak 28 is carried by a U-shaped strap or 70 fulcrum member having side bars 30 and a cross bar 31, the latter carrying the beak 28. The side bars 30 are pivoted to the rigid jaw bar 1 and to the movable jaw bar 3 at 75 32 and 32' respectively. Therefore, when there is relative longitudinal movement between the bars, there will be a tilting movement of the beak 28. The beak 29 is provided with a supporting bracket portion 33, which is fastened to the rigid jaw member 80 by a fastening device shown as a screw 34.

By reference to Fig. 1 it will be observed that the expanders are normally open or moved into expanding position when the handles 2 and 4 are spread apart. However, 85 the two expanding members 28 and 29 come together so that they can be inserted into the groove of the clamp 21. Then by exerting pressure on the grips of the handles 2 and 4, the expanders can be moved apart to 90 open up the crimped clamp 21 so as to leave the groove wide enough to receive the lens frame 23.

An important feature of my invention is the means for positioning the lens frame in 95 the clamp 21 preparatory to exerting the crimping or clamping action thereupon by the jaw faces 8 and 9. This consists of a spring-retracted, pivoted lens-frame-holding finger. By reference to Fig. 3 it will be observed that a spring-retracted pin 35 passes through the rigid jaw member 1 and on one side of the jaw member is a coil spring 35', one end of which bears against the jaw bar 1 and the other against the head or button 105 36 on the end of the pin 35. The other end of the pin extends beyond the opposite face of the jaw bar 1 and rigidly supports a sleeve 37, in the upper portion of which is an elongated slot 38, through which projects a stud 39 supporting a lens-rim-engaging fingers 40 having a beak 41 at right angles to its upper edge and adapted to engage in the groove 42 of the lens frame 23 to hold it in intimate engagement with the clamp 21 110 while the jaws 8 and 9 are expanded preparatory to applying pressure.

It will be observed that the finger 40 is vertically adjustable with respect to the sleeve 38 so that it can find the center of 120 the groove of the lens frame 23 and that the sleeve 37 is rigid on the pin 35 and the pin 35 rotatable within the jaw bar 1 as well as having spring-retracted longitudinal movement with respect thereto so that the lens frame positioning device can be moved out of functional position if desired by simply pressing on the button 36 and using it to turn the pin 35, the finger 40 having swinging movement about the axis of the 125 130

pin 35, as will be clearly apparent by reference to Fig. 3.

It will be apparent from the foregoing description in connection with the accompanying drawings that a novel form of optician's tool is provided, which is capable of assisting in the repairing of spectacles, nose glasses and the like so that the necessary repairs can be made.

10 In Fig. 7 I have shown a slightly modified form of tool in which the jaw 8 is provided with a notch 43, aligning with the notch 44 in the jaw bar 1 to receive the side bar 45 of a nose piece 46 for spectacles so 15 that there will be room enough to receive the clamp corresponding to clamp 21. The spectacle nose piece 46 is shown in dotted lines so as not to obstruct the position of the jaws shown in the modification.

20 What I claim and desire to secure by Letters-Patent is:

1. In a tool of the class described, a rigid jaw member, a movable jaw member slidable with respect to the rigid jaw member, means 25 for actuating the slidable jaw member to bring the effective parts of the jaw members together to clamp the frame clamps of an eye-glass mounting, and a frame positioning and holding means carried by the rigid jaw 30 member for holding the frame in the groove in the clamp of the eye-glass mounting.

2. In a tool of the class described, a rigid jaw member, a movable jaw member slidable with respect to the rigid jaw member, means 35 for actuating the slidable jaw member to bring the effective parts of the jaw members together to clamp the frame clamps of an eye-glass mounting, and a spring-actuated frame holding member carried by the rigid 40 jaw member for holding the frame in the

groove in the clamp of the eye-glass mounting.

3. In a tool of the class described, a rigid jaw member, a movable jaw member slidable with respect to the rigid jaw member, means 45 for actuating the slidable jaw member to bring the effective parts of the jaw members together to clamp the frame clamps of an eye-glass mounting, and a spring-actuated lens frame holder rotatable about a fixed axis 50 so that it may swing into and out of functional position and capable of holding the lens frame in engagement with the nose piece clamp so that the jaws of the tool may 55 clamp the tool together.

4. In a tool of the class described, two co-operating jaw members, one of which is relatively rigid and the other of which has relative movement with respect thereto, an outstanding lip on the outer edge of the rigid 60 member, a swinging lip in line with the first named lip and pivotally connected to the rigid member, and means co-operating with the movable member to cause the swinging lip to move toward and away from the rigid 65 lip when the movable member has movement imparted to it.

5. In a tool of the class described, two co-operating jaw members, handles for operating them, one of the jaw members consisting of a bar and the other having a right angular projection and provided with a cross groove in the projection and a transverse groove in the main portion of the jaw member, the other jaw having a longitudinal 70 groove coinciding with the first named groove in the complementary jaw, and means 75 for actuating said jaws.

In testimony whereof I affix my signature.
JAMES M. LAWLOR.
